UNITED STATES PATENT OFFICE.

JOHN C. McVEY, OF KANSAS CITY, MISSOURI.

FENCE-POST.

No. 813,816.

Specification of Letters Patent.

Patented Feb. 27, 1906.

Application filed December 7, 1905. Serial No. 290,748.

To all whom it may concern:

Be it known that I, JOHN C. McVEY, a citizen of the United States, residing at Kansas City, in the county of Jackson and State of Missouri, have invented new and useful Improvements in Fence-Posts, of which the following is a specification.

My invention relates to improvements in fence-posts.

One object of my invention is to provide a fence-post of cementitious material having embedded therein a novel reinforcing-frame, the whole forming a post which is cheaply constructed, of great strength, and which will withstand for a long period the action of the elements.

My invention provides, further, a fence-post having a longitudinal groove adapted to receive therein vertically-adjustable fence-wire-engaging devices constructed in a manner such that they may be readily mounted in the groove of the fence-post and firmly secured to the fence-wires.

My invention provides, further, a fence-post having a longitudinal groove in one side and a plurality of vertically-adjustable wire-engaging devices mounted in the groove of the post, said groove being dovetail in shape and the wire-engaging devices being each formed of sheet metal fitted to said groove, each device having two arms projecting beyond the face of the post, each arm having beyond the face of the post a notch to receive the adjacent fence-wire, the arms of each device being foldable toward each other and rearwardly across the fence-wire held in said notches.

Other novel features of my invention are hereinafter fully described and claimed.

In the accompanying drawings, illustrating my invention, Figure 1 is a front elevation view of my improved fence-post, showing the fence-wires secured thereto. Fig. 2 is a perspective view of the wire framework that is embedded in each post. Fig. 3 is a perspective view of one of the fence-wire-engaging devices detached from the post and shown engaged with a fence-wire. Fig. 4 is a cross-section taken on the dotted line $a'b$ of Fig. 5. Fig. 5 is a front elevation view of a portion of the fence-post, showing mounted in the groove in different positions three fence-wire-engaging devices. Fig. 6 is a cross-section taken

on the dotted line $c'd$ of Fig. 1. Fig. 7 is a front elevation view of my improved fence-post, showing mounted in the longitudinal groove a wooden strip to which the fence-boards are secured. Fig. 8 is a perspective view of the fence-post looking at the rear side thereof and showing the fence-wires secured thereto. Fig. 9 is a cross-section taken on the dotted line $e'f$ of Fig. 7. Fig. 10 is a perspective view of a wooden strip adapted to be mounted in the fence-post groove.

Similar characters of reference denote similar parts.

1 denotes the fence-post, substantially rectangular in cross-section and composed of cementitious material molded in the proper form in suitable molds provided for the purpose. The cementitious material is preferably composed of sand and cement mixed with water and placed in a plastic state in the mold, in which the material is permitted to harden. In the face of the post along a portion of its length is provided a longitudinal dovetail groove 2, adapted to receive therein the devices which support the longitudinal fence members comprising the fence-wires 3. When the post is molded, a reinforcing-framework is embedded in the cementitious material. This framework comprises four longitudinal binding members, comprising, preferably, four metal wires 4, 5, 6, and 7, disposed in pairs parallel with each other upon 75 oppositely sides, respectively, of the groove 2. 80

Each pair of longitudinal wires has connected, respectively, to its members a plurality of cross members composed, preferably, of metal wires 8. A plurality of transverse 90 members 9, preferably of wire, connect, respectively, opposite members 8. The wires 4, 5, 6, and 7 are provided each with two loops 10, disposed one above the other. Crossed wires 11 connect, respectively, the 95 lower loops 10 with the oppositely-disposed upper loops 10 of the wires 6 and 7. Similar crossed wires 12 are similarly connected to the upper and lower loops 10 of the wires 4 and 5. The wires 4, 5, 6, 7, 8; 9, 10, 11, and 12 when connected together, as shown in Fig. 2, and embedded in the cementitious material of the fence-post reinforce said post and prevent its being broken. The groove 2 is provided with two longitudinal recesses 13, 100 disposed, respectively, where the sides of the 105

groove intersect the rear wall of the groove. In the groove 2 are mounted a plurality of longitudinally-adjustable wire-engaging devices 14, each composed of sheet metal formed 5 to fit the groove 2 and provided each with two forwardly-extending arms 15, which project beyond the face of the fence-post and are provided each in one edge beyond the face of the post with a notch 16, adapted to receive 10 therein the adjacent wire 3. Each of the devices 14 prior to being fitted into the groove 2 has its rear side forwardly curved, as shown in Fig. 4. The arms 15 where they join the rear portion are inwardly bent, thus forming shoulders 17, adapted to enter the longitudinal recesses 13. The curvature of the rear portion of each device 14 is provided in order that the device may be readily inserted in the groove 2 at any point thereof and then 15 turned to a position in which the device will be disposed as shown in Fig. 4.

To attach the fence-wires 3 to the devices 14, the following-described operation is performed: Each device 14, having the form 25 shown in Fig. 4, is inserted in the groove 2 in the position occupied by the upper of said devices shown in Fig. 5. The device is then turned first to the position occupied by the middle device in Fig. 5 and then to the position 30 occupied by the lowest of the devices 14 in Fig. 5, which position corresponds to that shown in Fig. 4. The rear portion of the device is then flattened, as shown in Fig. 6, thus forcing the shoulders 17 into the longitudinal recesses 13 and forcing the arms 15 against the side walls of the groove 2. When so formed, the device 14 will be firmly retained in the dovetail groove of the post. The adjacent fence-wire 3 is then slipped into the 35 notches 16, after which those portions of the arms outside the recesses 16 are folded toward each other and then rearwardly across the fence-wire, as shown in Fig. 3 and Fig. 6, thus securely affixing the fence-wire to the 40 device. It is obvious that prior to the flattening of the rear portion of the device said device may be adjusted longitudinally in the groove 2 to the position desired. Opposite sides of the fence-post 1 in the portion thereof 45 adapted to be buried in the ground are provided with recesses 18, which when the post is set has the adjacent earth packed therein, thus more securely holding the post in the ground. For the purpose of lightening the 50 post the side opposite the groove 2 may be provided with longitudinal recesses 19.

If it is desired, instead of using wires as the longitudinal members of the fence, to employ boards for such purpose, the devices 14 55 are dispensed with and a vertical dovetail wooden strip 20 is fitted in the groove 2, as shown in Figs. 7 and 9. The fence-boards 21

are then nailed in the ordinary manner to said strip.

It will be obvious that various modifications of my invention may be made without departing from its spirit.

Having thus described my invention, what I claim, and desire to secure by Letters Patent, is—

1. The combination with a cementitious fence-post having a longitudinal groove in one side, the groove being dovetail shape, of a plurality of metal fence-wire-engaging devices longitudinally adjustable in said groove, 75 each of said devices being formed of sheet metal fitting said groove and provided each with two arms extending beyond the face of the post, said arms having each in one edge beyond the face of the post a notch adapted to receive therein the fence-wire, said arms being foldable toward each other and foldable inwardly across the fence-wire embraced thereby.

2. The combination with a cementitious fence-post having in one side a longitudinal groove of dovetail shape, said groove having two longitudinal recesses disposed respectively where the side walls intersect the rear wall of the groove, of a plurality of fence-wire-engaging devices mounted in said groove, each of said devices being composed of sheet metal and provided each with a forwardly-curved rear portion adapted to be flattened and when flattened entering said 95 recesses respectively, each device having two arms projecting beyond the face of the post, each arm having in one edge a notch adapted to receive the fence-wire, the arms of each device forward of said notches being foldable 100 toward each other and across the fence-wire.

3. The combination with the fence-post having in one side a longitudinal groove of dovetail shape, of a wire-engaging device longitudinally adjustable in said groove and composed of sheet metal fitted to the walls of said groove, said device having two arms projecting beyond the face of the fence-post, each of said arms having in one edge beyond the face of the post a notch adapted to receive therein the fence-wire, said arms being foldable toward each other and rearwardly 110 across the fence-wire.

4. The combination with a fence-post having on one side a dovetail groove disposed longitudinally and having two longitudinal recesses disposed respectively where the side walls intersect the rear wall of the groove, of a wire-engaging device longitudinally adjustable in said groove and composed of sheet metal, said device having a forwardly-curved rear portion adapted to be flattened and when flattened entering said recesses, said device having two arms projecting beyond 120

the face of the post, each arm having in one edge a notch to receive the fence-wire, said arms being foldable toward each other and rearwardly across the fence-wire.

5 5. The combination with the fence-wire, of the post having a longitudinal dovetail-shape groove, and a wire-engaging device of sheet metal formed to fit said groove and provided with two arms projecting beyond the face of the post, each arm beyond the face of the post having a notch to receive the fence-wire, said arms being foldable toward each other and rearwardly across the fence-wire.

10 6. The combination with the fence-wires, of the post having a longitudinal dovetail-shape groove, and a plurality of wire-engag-

ing devices longitudinally adjustable in said groove, each device being made of sheet metal formed to fit said groove and provided each with two arms projecting beyond the face of the post, each arm having in one edge a notch to receive the adjacent fence-wire, said arms of each device being foldable toward each other and rearwardly across the fence-wire held in the notches.

In testimony whereof I affix my signature in presence of two subscribing witnesses.

JOHN C. McVEY.
